United States Patent Office

Des. 188,635
Patented Aug. 16, 1960

188,635

BOAT

Henry Donald Canazzi, 178 Jewett Parkway,
Buffalo, N.Y.

Filed Mar. 23, 1959, Ser. No. 55,117

Term of patent 7 years

(Cl. D71—1)

Fig. 1.

Fig. 2.

Fig. 3.

Fig. 4.

The dominant features of the design reside in the portions shown in full lines.

I claim:

The ornamental design for a boat, substantially as shown and described.
